CLAIM

The ornamental design for a clog, as shown and described.

DESCRIPTION

FIG. 1 is a front, right and top perspective view of a clog, showing our design for a left foot.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a partial enlarged view of an area labeled “9” in FIG. 1; and,

FIG. 10 is a partial enlarged view of an area labeled “10” in FIG. 2.

A clog for a right foot is a mirror image of the clog for the left foot as shown in FIGs. 1 to 8 and is also claimed.

The dot-dash broken lines framing portions of the clog in FIGS. 1, 2, 9, and 10 illustrate areas of enlargement and form no part of the claimed design.
